METHOD AND MOLD FOR FORMING ICE OBJECTS Thomas F. Sherblom, 6665 Santa Monica Blvd.,
Los Angeles, Calif.

Filed Oct. 24, 1955, Ser. No. 542,161

2 Claims. (Cl. 62—355)

This invention relates to a method and mold for forming ice objects and has particular application in the formation of decorative ice statuary and the like which is utilized at banquets and similar functions to decorate the banquet table in a unique and impressive manner. Such ice statuary also has application in the decoration of the windows of restaurants and the like.

While such ice sculpture can be created manually by a sculptor actually carving the desired representation from a block of ice, the carving of the block of ice is a time-consuming task and in many localities there are not available artists of sufficient skill to provide ice statuary to the restaurant and hotel trade.

Therefore, attempts have been made in the past to create such ice statuary by the use of molds formed from metal, or the like, and defining cavities configured to represent the shape of the object to be molded. In the prior art utilization of such molds it has been necessary to place the mold in a can, such as the typical can used in forming blocks of ice, the mold and the can being filled with water and the can subsequently being immersed in a brine tank.

After the water in the can has frozen, simultaneously with the water in the interior of the mold, the can is removed from the brine tank and the ice formed about the mold must be first chipped away to expose the mold and to permit the removal of the statuary from the interior thereof. Exemplary of the prior art teachings is my Patent No. 2,545,592 wherein is disclosed a method of forming ice molded figures by the utilization of a split mold adapted to be immersed in a can and which is subsequently disposed in a brine tank. However, the apparatus necessary for the practice of prior art methods has been relatively cumbersome and has precluded the adoption of these methods by relatively small restaurants, hotels and the like.

It is, therefore, an object of my invention to provide a method and mold for forming ice objects which can be readily utilized by individual hotels and restaurants and which does not entail the use of large brine tanks customarily found in large metropolises and not available in smaller cities and towns.

The necessity for using the can filled with water in conjunction with the prior art molds has arisen because of the fact that all molds have relatively constricted areas of small dimensions and these relatively constricted areas would freeze immediately if the mold were directly immersed in the brine tanks without first suspending them in cans of water which are then immersed in the brine tanks. Since the water in the cans freezes inwardly at a uniform rate about the molds, the premature freezing of the liquid within the molds at the constricted areas thereof is eliminated. However, when the freezing process is accomplished the large body of ice formed about the molds must be chipped away and removed prior to the removal of the statuary from the interior of the mold.

Another object of my invention is the provision of a mold for freezing ice objects which includes a mold cavity

2

defined by a plurality of mold sections and wherein each of said mold sections is provided with an insulating chamber adapted to effectively prevent the premature freezing of the liquid within the cavity at constricted portions of the mold. By the provision of a mold of this character, I have been able to eliminate the necessity for the use of the conventional can in which conventional molds are immersed and thus there is no necessity for chopping a block of ice away from the exterior of the mold once the freezing process has been accomplished.

In addition, the mold can be suspended in a brine tank equivalent in dimensions to the can previously utilized and suspended in a large brine tank and thus it is possible to provide a plurality of molds and a brine tank of sufficient size to accommodate any one of the molds to small hotels and restaurants or to hotels and restaurants in small cities or towns for their individual use at a relatively moderate price.

An additional object of my invention is the provision of a mold of the aforementioned character which is constituted by a plurality of mold sections which, together, define a mold cavity of the desired configuration, each of the sections being provided with an insulating chamber containing a mass of insulating material.

A further object of my invention is the provision of a mold of the aforementioned character wherein the thickness of the material in the insulating chambers of the individual sections of the mold is inversely proportional to the dimensions of the mold cavity constituted by said mold sections when they are joined in operative relationship by fastening means associated therewith.

An additional object of my invention is the provision of a method of forming a molded ice object which includes the steps of filling a mold cavity with a liquid susceptible to freezing, the application to the exterior of the mold of an insulating medium and the subsequent immersion of the mold and the insulating medium encompassing the same in a freezing medium to create the molded ice object.

Other objects and advantages of my invention will be apparent from the following specification and the accompanying drawing which is for the purpose of illustration only and in which:

Fig. 1 is a utility view showing the method of immersing a mold constructed in accordance with the teachings of my invention in a brine tank;

Fig. 2 is a perspective view showing a molded ice object;

Fig. 3 is a perspective view showing a plurality of mold sections constituting the mold of my invention;

Fig. 4 is a perspective view showing the mold sections joined in operative relationship with each other;

Fig. 5 is a vertical, sectional view of the mold taken on the broken line 5—5 of Fig. 4; and

Fig. 6 is an enlarged, fragmentary view showing the gasket and fastening means associated with the mold sections of my invention.

Referring to the drawing and particularly to Figs. 1—5 thereof, I show a mold 10 constructed in accordance with the teachings of my invention and incorporated in a housing 12 which is constituted by a plurality of mold sections 14 adapted to be operatively connected by fastener means 16, to be described in greater detail hereinbelow.

The housing 12 and each of the mold sections 14 constituting the same are substantially rectangular in configuration, in the present embodiment of my invention, but it is, of course, not intended that there be any limitation whatsoever as to the external configuration of the housing 12 and the mold sections 14. The mold sections 14 can be fabricated from any rigid or semi-rigid ma-

terial, such as plastic impregnated fiber glass, plastic, metal, or hard rubber.

Each of the mold sections 14 incorporates an insulating chamber 18 whose exterior wall is constituted by the exterior wall of the section and whose interior wall 20 is configured, as at 22, to define a portion of the shape of a molded article 23, best shown in Fig. 2 of the drawing.

When the mold sections 14 are joined in operative relationship with each other by the fastening means 16, a mold cavity 24 is defined by the juxtaposed interior walls 20 of the mold sections 14, as best shown in Fig. 5 of the drawing. The mold cavity 24 is characterized by the fact that at different points within the interior thereof the dimensions of said cavity are relatively small and constitute restrictions in said cavity, while at other points the dimensions of the cavity 24 are relatively large.

This is exemplified in Fig. 5 of the drawing wherein the bell segment 26 of the cavity 24 is relatively large and wherein certain other portions 28 of the cavity 24 are restricted and relatively small. In order to provide for the uniform freezing of a liquid disposed within the mold cavity 24, there is deposited in the insulating chambers 18 of the sections 14 of the mold 10 a mass 30 of insulating material which can be constituted by rock 25 wool, polystyrene, fiber glass, or the like.

In some applications it may be possible to depend upon the insulating effect of a vacuum created between the exterior wall of each of the mold sections 14 and the interior wall 20 thereof, or an inert gas can be sealed 30 in the individual insulating chambers 18.

In a mold constituted by the interior walls 20 alone were to be deposited in a brine tank 34, such as that shown in Fig. 1 of the drawing, practically immediate freezing of the liquid in the constricted sections 28 of the mold would take place, preventing free circulation of the fluid in the interior of the mold and the creation of a molded object 23 characterized by the absence of bubbles or inclusions therein. Such premature freezing is particularly critical where the intermediate, restricted portions 28 are disposed between larger areas in the mold and the premature freezing of said restricted portions of the mold cavity 24 prevents free flow of liquid between the larger portions of the cavity 24. Therefore, it was necessary in prior art methods to deposit the molds in the can full of water prior to immersing them in the brine solution 36 in the brine tank 34.

However, in the present embodiment of my invention the insulating chambers 18 and the mass of insulating material 30 deposited therein prevent the premature freezing of the fluid in the mold 10 since the restricted areas 28 of the mold cavity 24 are surrounded by a greater mass of insulating material 30 than are the larger dimensioned portions thereof such as the bell portion 26 of the mold cavity 24. Thus, when the mold 10 is deposited in the brine tank 34, the freezing of the fluid within the mold cavity 24 is initiated in those portions of the mold, such as the larger dimensioned bell portion 26, which are least insulated and is prevented in the restricted portions 28 which are most completely insulated. Thus, the freezing of the fluid within the mold cavity 24 progresses inwardly toward the center of the mold cavity and premature freezing of the fluid located in the restricted portions 28 of the mold cavity 24 is prevented.

Each of the mold sections 14 is provided with a contiguous peripheral flange 40 and in one of the flanges there is installed a resilient sealing gasket 42 which engages the adjacent surface of the other contiguous flange when elongated resilient strips 46 formed from stainless steel or the like and constituting the fastening means 16 are slid over the contiguous flanges 40 to maintain the mold section 14 in operative relationship with each other.

In utilizing the mold 10 and practicing the method of my invention, I first join the mold sections 14 in operative relationship with each other by applying the elongated

resilient strips 46 constituting the fastening means 16 to the contiguous flanges 40 thereof. The mold sections 14, when so fastened together, are isolated from brine leakage by the presence of the fluid-tight gasket 42 between the contiguous surfaces of the flanges 40 on the mold sections 14.

When thus disposed in operative relationship, the interior walls 20 of the mold sections define the mold cavity 24 which is then filled with a fluid susceptible to freezing, such as water, which is aerated continuously through air hoses 48 during the freezing process to produce a frozen object 23 characterized by the clarity of the ice from which it is molded. The molds 10 are disposed in the brine 36 in a brine tank 34 and the brine circulated thereabout until the freezing of the object 23 within the mold 10 has been accomplished.

After freezing is complete, the mold 10 is removed from the brine tank 34 and permitted to stand a sufficient time to slightly melt the molded object and thus permit the mold sections 14 to be released therefrom after the removal of the fastening means 16 from operative relationship with the flanges 40 of said mold sections.

Although the brine tank 34 is shown in Fig. 1 as adapted for the reception of a plurality of molds for simultaneous freezing, it is within the concept of my invention to provide a relatively small brine tank of a quasi-portable nature which can be readily installed by a small restaurant or hotel and which is adapted for the reception of only one mold. Therefore, the formation of molded ice objects of the character of the molded object 23 shown in Fig. 2 of the drawing becomes feasible by organizations and in localities where such molded ice objects have not been previously available.

I claim as my invention:

35. 1. In a die for creating a molded ice object, the combination of: a housing constituted by a plurality of sections, each section including an outer wall and an inner wall spaced from said outer wall to define an insulation receiving chamber, said inner walls constituting a mold 40 to define a portion of the shape of an ice object to be formed therein; an insulating body permanently disposed in the chamber of each of said sections and in continuous engagement with said inner wall; fastening means for joining said sections in operative relationship with each other to juxtapose the inner walls of said sections and to define a cavity for the reception of fluid to be frozen; and sealing means interposed between said sections for isolating said cavity from a surrounding body of refrigerant in which said die is immersed.
50. 2. In a mold for forming ice objects, the combination of: a mold body for forming a three dimensional object constituted by a plurality of sections, each section incorporating an insulating chamber the inner wall of which is constituted by a mold defining a portion of the shape of said object and having an angularly extending fastener 55 engageable portion thereupon; sealing means mounted in operative relationship with one of said sections and engageable with the other of said sections; a body of insulating material permanently disposed in the chamber of each of said sections and in continuous engagement with said inner wall; and fastening means engageable with the angularly extending fastener engageable portions of said sections to maintain said sections in operative relationship with each other and to urge said sealing means on said 60 one section into engagement with the other section to prevent infiltration of a surrounding fluid into the interior mold defined by the juxtaposed inner walls of said sections.
